UNITED STATES PATENT OFFICE.

ARTHUR L. STAPLES, OF NEW HAVEN, CONNECTICUT, ASSIGNOR TO WINCHESTER REPEATING ARMS COMPANY, OF NEW HAVEN, CONNECTICUT, A CORPORATION OF CONNECTICUT.

ROLLER-SKATE ROLL.

Application filed May 6, 1921. Serial No. 467,234.

To all whom it may concern:

Be it known that I, ARTHUR L. STAPLES, citizen of the United States, residing at New Haven, in the county of New Haven, 5 and State of Connecticut, have invented new and useful Improvements in Roller-Skate Rolls, of which the following is a specification.

My invention relates to ball-bearing skate- 10 rolls of the enclosed or so-called "military" type, and has for its object to provide a roll which can be manufactured at a low cost, which shall contain a minimum number of parts, and which by a slight change 15 of proportion may be adapted to contain either a single or double row of balls.

A further object is to provide a roll having a truss strengthened support between the rim and the hub suitable for withstand- 20 ing lateral as well as radial strains incident to its use on a roller-skate.

In the accompanying drawings, which show the preferred embodiment of my invention,—

25 Fig. 1 is a sectional view of a roll made in accordance with my invention, and containing a single row of balls;

Fig. 2 is a sectional view of a roll made in accordance with my invention, and con- 30 taining a double row of balls;

Fig. 3 is a side view of a skate roll made in accordance with my invention;

Fig. 4 is a view of one of the shouldered rivets used to unite the side plates of the 35 roll;

Fig. 5 is a sectional view of a modifica- 40 tion of my invention, wherein a plain rivet, together with a separate collar or washer is used in place of the shouldered rivet shown in the preceding figures;

Fig. 6 is a detailed view of the collar, and Fig. 7 is a detailed view of the rivet, shown in Fig. 5.

In constructing a roll according to my in- 45 vention, I employ two similar side plates 10, preferably stamped of sheet metal having inwardly-bent rim-forming portions 11 with their edges adapted to register evenly in close abutment. These 50 side plates are exact duplicates of each other, and therefore may be produced by the same dies. The side plates 10 are further formed with depressed web portions 13 preferably flat, which are joined to the rim 55 portions by portions 12, preferably inclined

inwardly and have outwardly-bent hub por- tions 19 to form an inwardly concave race- way for the balls 20.

The cooperating raceway for the balls 20 may be formed as shown in the spindle 21 mounted axially within the roll and which may be attached to the skate in any desired manner. If it is desired to use a single row of balls in the roller, a spindle of the form shown in Fig. 1 may be employed, while if a double row of balls is desired, the form shown in Fig. 2 should be used. In the latter case, the hub portions 19 of the plates are adjusted somewhat farther apart, as shown.

70 Various means may be employed to firmly unite the plates together in forming the roll, but I preferably so unite them as to space the depressed web portions 13 apart, thereby lessening the necessity for any sharp 75 bending of the plates 10, and also so as to obtain a trussed construction between the side plates for withstanding lateral and radial strains to which the roller is subjected when in use on roller-skates. In one em- 80 bodiment I have employed shouldered rivets 15 of the form shown in Fig. 4 to fasten the plates 10 together. The enlarged or shouldered portions 16 of the rivets 15 serve to space the webs 13 apart and the reduced end 85 portions are received in the openings 14 of the plates for being headed over the same as shown. Three of such rivets at equally spaced intervals around the plates have been found to suffice, as shown in Fig. 3.

90 Another embodiment of fastening and separating means for the plates is shown in Fig. 5, wherein a plain cylindrical rivet 22, together with a separate collar or washer 23 between the plates, is employed to hold the 95 side plates in assembled position. A threaded stud or other equivalent mechanical element secured to the plates might be used for this purpose if desired, and in some cases the plates might be united to an intervening 100 spacing member by spot-welding or equivalent means.

What I claim is,—

1. A skate roll comprising two side plates having inwardly bent rim portions abut- 105 ting in edge-to-edge contact only, inter- mediate annular web portions disposed in closely adjacent parallel relation, and out- wardly bent hub portions, said hub portions having inner concave faces to provide ball 110

- 2 races, said rim, web and hub portions being integral in each side plate, and means for rigidly securing together said side plates at the parallel web portions thereof.
- 5 2. A skate roll comprising two side plates having inwardly bent rim portions abutting in edge-to-edge contact only, intermediate annular web portions disposed in closely adjacent parallel relation, and outwardly bent hub portions, said rim, web and hub portions being integral in each side plate, means interposed between the web portions of each side plate for spacing apart and stiffening the same, and means for rigidly securing together said side plates and holding said web portions in engagement with said spacing means.
- 10 3. A skate roll comprising two side plates having inwardly bent rim portions abutting in edge-to-edge contact only, intermediate annular web portions disposed in closely adjacent parallel relation, and outwardly bent hub portions, said rim, web and hub portions being integral in each side plate, rivets rigidly connecting said side plates, and shoulders on said rivets engaging each of said side plates for spacing apart and stiffening the annular web portions thereof.
- 15 4. A skate roll comprising two side plates having inwardly bent rim portions abutting in edge-to-edge contact only, flat annular portions disposed in closely adjacent parallel relation, web portions inclined inwardly from said rim portions connecting the latter with said flat portions, hubs turned outwardly from said flat portions and having their inner faces concave to provide ball races, rivets extending through said flat portions for securing together the side plates, and shoulders on said rivets for engaging each of said flat portions to space the latter apart.
- 20 5. In a skate roll the combination of two side plates having integral inwardly bent rim portions, inwardly inclined intermediate portions, flat annular web portions and inwardly concave ball-race-forming portions with means for rigidly connecting said flat annular web portions of said side plates, the said inwardly bent rim portions abutting against each other with edge-to-edge contact only.
- 25 6. In a skate roll the combination of two side plates having integral inwardly bent rim portions, inwardly inclined intermediate portions, flat annular web portions and inwardly concave ball-race-forming portions with means for spacing and rigidly connecting said flat annular web portions of said side plates, the said inwardly bent rim portions abutting against each other with edge-to-edge contact only.
- 30 7. In a skate roll the combination of two side plates having integral inwardly bent rim portions, inwardly inclined intermediate portions, flat annular web portions and inwardly concave ball-race-forming portions with shouldered rivets for rigidly connecting said flat annular web portions of said side plates, the said inwardly bent rim portions abutting against each other with edge-to-edge contact only.

In testimony whereof I have affixed my signature.

ARTHUR L. STAPLES.
